Des. 187,712
Patented Apr. 19, 1960

187,712

KNOB FOR DRAWERS, DOORS AND THE LIKE

Don Heyer, El Monte, and James W. Maize, La Habra, Calif., assignors to M and H Industries, Inc., Los Angeles, Calif., a corporation of California

Application October 27, 1958, Serial No. 53,161

Term of patent 14 years

(Cl. D50—3)

Fig. 1.

Fig. 2.

Fig. 3.

Fig. 1 is a front elevational view of a knob for drawers, doors and the like, showing our new design;

Fig. 2 is a view in side elevation thereof; and

Fig. 3 is a sectional view taken on the line 3—3 of Fig. 1, with a portion of the knob shown in elevation.

We claim:

The ornamental design for a knob for drawers, doors and the like, as shown.
